UNITED STATES PATENT OFFICE.

ADOLPHE LE MOULT, OF NEW YORK, N. Y.

DESIGN FOR A MOURNING FLOWER-PIECE.

SPECIFICATION forming part of Design No. 17,490, dated July 26, 1887.

Application filed June 18, 1887. Serial No. 241,800. Term of patent 7 years.

To all whom it may concern:

Be it known that I, ADOLPHE LE MOULT, of the city, county, and State of New York, have invented a new and original Design for a 5 Mourning Piece, of which the following is a specification.

The design relates to a flower-piece for funerals and mourning purposes generally; and it consists of a flower-piece formed of a base, a 10 central pillar, a wreath wound around said pillar, an inclined scale-beam, a tongue, and conventional representation of scale-pans, one pan containing a crown, palm leaves, and a dove, and the other flowers.

15 The nature of my design is fully shown in the accompanying drawing, to which reference is made.

A in the drawing represents the base, and B the central pillar, of my design for a mourning flower-piece.

20 C represents an inclined scale-beam; D', the tongue of the same, which is located in an ornamental top piece, B', of the pillar B. A wreath, b, is wound spirally around the pillar B.

25 E E' are conventional representations of scale-pans that are suspended from the scale-beam C, the lower pan being ornamented with a crown, E', palm-leaves E'', and a dove, E'', perched on a leaf. The upper pan is ornamented with flowers and the like. The whole

represents an ornamental mourning flower-piece.

Having thus described my design, I claim as new and desire to secure by Letters Patent—

35 1. The design for a mourning flower-piece, as herein shown and described, composed of a base, a central pillar, a spiral wreath around said pillar, an inclined scale-beam, conventional representations of scale-pans, and ornamental pieces in said scale-pans, substantially as set forth.

40 2. The design for a mourning flower-piece, as herein shown and described, composed of a base, an upright center pillar, a spiral wreath 45 around said pillar, an inclined scale-beam, a tongue, an ornamental top piece on the pillar, conventional representations of scale-pans at the end of the scale-beam, and a crown, palm-leaves, and dove in the lower scale-pan, and 50 flowers in the upper scale-pan, substantially as set forth.

55 In testimony that I claim the foregoing as my invention I have signed my name in presence of two subscribing witnesses.

ADOLPHE LE MOULT.
